UNITED STATES PATENT OFFICE.

GEORGE BELIA NORTON, OF JONESVILLE, MICHIGAN.

DESIGN FOR A FIRE-BACK PLATE.

SPECIFICATION forming part of Design No. 15,345, dated August 26, 1884.

Application filed June 22, 1884. Term of patent 7 years.

To all whom it may concern:

Be it known that I, GEORGE B. NORTON, a citizen of the United States, residing at Jonesville, in the county of Hillsdale and State of Michigan, have invented a certain new Design for Fire-Back Plates; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention and is a front view. Fig. 2 is a vertical section taken where the broken line $x-x$ is shown on Fig. 1.

This design has relation to fire-back plates for stoves; and it consists in the novel form and configuration of the face of the plate, having its surface below the curved top portion formed by oblique intersecting ribs and intervening diamond-shaped depressions, all as hereinafter shown and described.

25 In the accompanying drawings, the letter A

designates the plate of the fire-back, which has the upper portion curved backward, as shown at C. Below the curved portion of the plate A its face has oblique ribs D D, parallel to each other, and with oblique ribs E E, also parallel to each other, and intersecting the ribs D D in such a manner as to form diamond-shaped or lozenge-shaped depressions F. The surface of the plate below the top portion is in this manner made up of the intersecting 35 ribs and the intervening lozenge-shaped depressions.

What I claim; and desire to secure by Letters Patent, is—

The design for a fire-back plate, consisting 40 of the backwardly-curved plate A, having the oblique intersecting face-ribs D E and the intervening diamond-shaped depressions F, as shown and described.

In testimony whereof I affix my signature in 45 presence of two witnesses.

GEORGE BELIA NORTON.
